(57) **CLAIM**

The ornamental design for a bolt sorter, as shown and described.

DESCRIPTION

FIG. 1 is a perspective view of a bolt sorter looking towards a top side;

FIG. 2 is a perspective view of the bolt sorter of FIG. 1 looking towards a bottom side;

FIG. 3 is a left side elevational view of the bolt sorter of FIG. 1;

FIG. 4 is a right side elevational view of the bolt sorter of FIG. 1;

FIG. 5 is a rear side elevational view of the bolt sorter of FIG. 1;

FIG. 6 is a front side elevational view of the bolt sorter of FIG. 1;

FIG. 7 is a top plan view of the bolt sorter of FIG. 1;

FIG. 8 is a bottom plan view of the bolt sorter of FIG. 1;

FIG. 9 is a perspective view of a bolt sorter looking towards a top side;

FIG. 10 is a perspective view of the bolt sorter of FIG. 9 looking towards a bottom side;

FIG. 11 is a left side elevational view of the bolt sorter of FIG. 9;

FIG. 12 is a right side elevational view of the bolt sorter of FIG. 9;

FIG. 13 is a rear side elevational view of the bolt sorter of FIG. 9;

FIG. 14 is a front side elevational view of the bolt sorter of FIG. 9;

FIG. 15 is a top plan view of the bolt sorter of FIG. 9; and,

FIG. 16 is a bottom plan view of the bolt sorter of FIG. 9.

The broken lines represent portions of the structure that forms no part of the claim.
